Intellectual Property Law, P.C.(57) CLAIM

The ornamental design for a barbecue, as shown and described.

DESCRIPTION

FIG. 1 is a front top perspective view of a first version of a barbecue showing the new design;

FIG. 2 is a front view thereof;

FIG. 3 is a side view thereof;

FIG. 4 is an opposite side view thereof;

FIG. 5 is a top view thereof; and,

FIG. 6 is a bottom view thereof.

The dashed lines shown in the drawings illustrate portions of the barbecue that are not claimed and thus form no part of the claimed design.
